LIGHTING FIXTURE

Edward B. Freed, 6607 Drexel, Los Angeles, Calif.

Filed May 2, 1962, Ser. No. 69,965

Term of patent 14 years

(Cl. D48—20)

FIG. 1 is a perspective view of a lighting fixture showing new design wherein the canopy is pole supported.

FIG. 2 is a side elevation thereof as seen in the direction of line 2—2 of FIG. 1, with one of the light members omitted for convenience of illustration.

FIG. 3 is a top plan view thereof.

FIG. 4 is a bottom plan view thereof.

FIG. 5 is a side elevation thereof showing the canopy in a ceiling supported position.

I claim:

The ornamental design for a lighting fixture, substantially as shown and described.
